UNITED STATES PATENT OFFICE

ISRAEL NOVICK, OF BOSTON, MASSACHUSETTS

DESIGN FOR A DETACHABLE SERVING STAND FOR A CHAIR

Application filed December 4, 1931. Serial No. 41,966. Term of patent 3½ years.

To all whom it may concern:

Be it known that I, ISRAEL NOVICK, a citizen of the United States, residing at Boston, county of Suffolk, Commonwealth of Massachusetts, have invented a new, original, and ornamental Design for a Detachable Serving Stand for a Chair, of which the following is a specification, reference being had to the accompanying drawings, forming a part thereof.

In the drawings:

Fig. 1 is a side elevation of a serving stand showing my new design.

Fig. 2 is a perspective view of the same.

I claim:

The ornamental design for a detachable serving stand for a chair, substantially as shown.

ISRAEL NOVICK.
